[57] **CLAIM**

The ornamental design for a support element for securing foil sheet wall insulation or the like, as shown and described.

DESCRIPTION

FIG. 1 is a top and rear perspective view of a support element for securing foil sheet wall insulation or the like showing my new design;

FIG. 2 is a horizontal cross-sectional view thereof, taken along line 2—2 of FIG. 1; and,

FIG. 3 is a front elevational view thereof.

The element is shown broken-away in the views to indicate indeterminate length.
